BEARING FOR PUMP OPERATING LEVERS

James P. Ratigan, Los Angeles, Calif.

Application September 22, 1930
Serial No. 483,402

5 Claims. (Cl. 308—21)

This invention relates to bearings of the type employed as the fulcrum of a pump operating lever, for example, a walking beam.

This is an improvement on my reissue patent No. 17,904, dated Dec. 16th, 1930, which patent described the advantage of employing a rocker type of bearing as the fulcrum for a pump operating lever.

An object of this invention is to improve the construction and operation of the bearing described in the above mentioned patent. In that patent, the construction admitted of lateral deflection of the walking beam in order that the said walking beam would be self-adjusting to properly align itself with the polish rod and the crank pin, but the construction did not permit of sufficient lateral swinging of the walking beam so that the end, to which the polish rod is connected, could be swung a sufficient distance to one side of the well to admit of performing other operations than pumping as, for example, pulling the pump and pump tubing.

Ordinarily, at the present time, the pitman end of a walking beam is tied down so as to elevate the polish rod end of the walking beam as high as possible above the well, when it is desired to pull the pump and pump tubing or perform other necessary operations in maintaining the well in production. When so tied down, the walking beam is more or less in the way and some attempt has been made in the past to provide a swivel bearing that will enable the walking beam to be swung laterally, as is provided for by this invention. A very important object of this invention is to simplify the construction that affords lateral swinging of the beam.

Another important object is to provide a simple construction that will permit automatic shifting of the fulcrum plane of the walking beam, as the beam operates, and, at the same time, permit of lateral swinging of the beam so that the beam will be self-aligning, in operation, and so that, when it is necessary to pull the pump or perform other operations, the polish rod end of the beam may be swung considerably to one side of the well.

Another important object is to improve the construction whereby articulation of the upper and lower bearing members is effected.

Another very important object is universal adjustability of the means for connecting one of the bearing members with the Samson post, in order that said bearing member may be firmly secured to Samson posts of different widths and, also, so that when it is desired to place said bear-

ing member on a Samson post previously provided with bolt holes for another type of bearing, adjustment of the securing means is possible, so that the same bolt holes in the Samson post may be employed.

Other objects and advantages will appear in the subjoined detailed description.

The accompanying drawings illustrate the invention:

Figure 1 is a side elevation of pump operating mechanism that includes a bearing constructed in accordance with the provisions of this invention.

Fig. 2 is a plan view of Fig. 1, the pump operating lever being shown in solid lines in pumping position and being shown in broken lines swung laterally out of pumping position.

Fig. 3 is an enlarged side elevation of the bearing shown in Figs. 1 and 2, the pump operating lever and the Samson post being indicated in broken lines.

Fig. 4 is a plan view of Fig. 3, the walking beam being indicated in two different positions in broken lines.

Fig. 5 is an elevation of Fig. 4 from the right thereof.

Fig. 6 is a vertical section on the line indicated by 6—6, Fig. 4. The pump operating lever and the Samson post are omitted.

Referring to the drawings, a pump operating lever is indicated at A, and, in this instance, said lever is in the form of a walking beam. The bearing or fulcrum of the walking beam A is indicated at B and said bearing is mounted on a Samson post C. Connected to one end of the lever A is a pitman D which is driven by a crank E that is operated in the usual manner. The other end of the lever A is connected by a suitable beam hanger F to a polish rod G which operates in a well indicated at H.

Since the invention has to do only with the bearing B, it, alone, will be described in detail herein. The bearing B includes two opposed members, an upper bearing member 7 constituting a rocker, and a lower member 8 which constitutes a support for the rocker 7 to rock upon.

The members 7, 8 are loosely articulated by suitable means so as to prevent the member 7 shifting horizontally upon the member 8, and these articulating means are constructed so as to permit of rocking of the member 7 in a vertical plane and, also, horizontal swinging of the member 7, and these means, in this instance, are constructed as follows: One of the members 7, 8, in this instance the member 8, is provided at its cen-

ter with a socket 9 and the other member, in this instance the member 7, is provided with a downwardly projecting stud 10 that loosely fits in the socket 9. The socket 9 has downwardly and inwardly tapered walls and, preferably, the stud 10 is substantially hemispherical in form so as to virtually produce a ball and socket connection between the members 7, 8. Of course, as the member 7 rocks, the stud 10 will be caused to rise and fall in the socket 9, but, owing to the hemispherical form of the stud and to the tapered construction of the socket, any slight horizontal shifting of the member 7, that might occur when the stud 10 is raised, is counteracted by reason of the slanting walls of the socket causing the stud 10 to be returned to axial position in the socket, upon downward movement of the stud.

In order to provide for rocking of the member 7, the underface 11 of said member is convex or arcuate when viewed in profile or, in other words, the member 7 is provided with a semicylindrical rocker portion 12. The ends of the portion 12 are connected by a bridging member 13, integral therewith, thus providing for a large opening 14 that extends from side to side of the member 7.

Through the opening 14 extends a retaining pin 15 that projects through supports 16 in the form of upstanding flanges of the bearing member 8. The pin 15 may be retained against longitudinal displacement by cotter keys 17 or their equivalents.

In plan, the side margins 18 of the portion 12 are arcuate so that the member 7 may be rotated horizontally about the axis of the stud 10 without interference between the margins 18 and the flanges 16. Preferably the marginal portions 18 constitute flanges of the portion 12, and the pin 15 projects through the member 7 between the margins 18 and the bridging member 13. Thus, it will be seen that the pin 15 is supported by the member 8 and is loose within the member 7.

Bolt holes 19 are provided in the bridging member 13 for bolting the bearing member 7 to the lever A, the bolts being indicated at 20.

Suitable means are provided for adjustably connecting the bearing member 8 to the Samson post C and, in this instance, this means is constructed as follows: the member 8 is provided with transversely extending key slots 21 to accommodate the heads 22 of bolts 23 which bolts are thus adjustable toward and from the sides of the Samson post C. The bolts 23 are in pairs, one pair at each side of the Samson post. The bolts of each pair pass through a connecting member 24 and the nuts 25 of the bolts, being adjustable on said bolts, afford vertical adjustment of the connecting members 24. Thus, longitudinal slots 26 in the members 24 may easily be caused to register with any bolt holes with which the Samson post may have been provided for bolting on of a bearing. Bolts 27 are shown passing through the slots 26, said bolts 27, in this instance, extending entirely through the Samson post, from side to side thereof, and through both members 24. It will thus be seen that the bearing member 8 may be readily secured to Samson posts of different widths by moving the bolts 23 in or out, that the slots 26 may be alined with any bolt holes, for bearing connections, that may have been previously provided in the Samson post, and that slots 26 provide for various spacing of the bolts 27 in order to accommodate them to various spacing of bolt holes that may have been provided in the Samson post.

The foregoing will make clear the construction

and operation of the invention and, briefly stated, the operation is as follows: operation of the pitman D swings the lever A up and down, thus causing the bearing member 7 to rock on the bearing member 8. As the bearing member 7 rocks, the pivotal axis of the lever A shifts horizontally. For example, when the polish rod is at the beginning of its upstroke, the load arm of the lever A will be shorter than when the polish rod is near the upper end of the stroke, a decided advantage, since the load is being picked up when the load arm of the lever is at a minimum. When the load arm is shortening, the power arm of the lever is lengthening, and, accordingly, the power is applied to the greatest advantage for operating the polish rod. The socket 9 and stud 10 prevent any material horizontal displacement of the member 7 with respect to the member 8 and the pin 15 prevents the member 7, in case it jumps off of the member 8, from being displaced horizontally sufficiently to result in falling of the lever A from its support. It will be seen in Fig. 3 that the length of the opening 14 is many times the diameter of the pin 15, thus not only permitting of free rocking of the member 7 but also permitting of the member 7 being turned in a horizontal plane through an angle of 90°, or 45° on each side of its normal operating position shown in Fig. 4 in solid lines. In Fig. 4 the member 7 is shown in broken lines turned to some extent out of its normal operating position. Thus, when it is desired to pull the pump or perform other operations attendant upon the maintaining of a well in production, the pitman D and the polish rod G will be disconnected from the lever A and then said lever will be swung so that its polish rod end is to one side or the other of the well, as indicated in broken lines in Fig. 2.

I claim:

1. A bearing for a pump operating lever comprising bearing members, the one provided with a rocker face resting on the other, a swivel joint means loosely articulating said members whereby the upper member may rock in a vertical plane and swivel in a horizontal plane, the rocker member provided with a transverse opening and said other member carrying a pin projecting through said opening, the length of said opening being considerably greater than the diameter of the pin to permit of horizontal swiveling of the rocker member.

2. A bearing for a pump operating lever comprising bearing members, the one provided with a rocker portion resting on the other and with an attaching portion spaced from the rocker portion to provide an opening, the side margins of the rocker portion being arcuate in plan, the other bearing member provided with flanges adjacent to the arcuate margins, and a pin mounted in the flanges and projecting through the opening, the length of said opening being considerably greater than the diameter of the pin to permit of horizontal swiveling of the first mentioned member.

3. A bearing for a pump operating lever comprising bearing members, the one provided with a rocker portion resting on the other and with an attaching portion spaced from the rocker portion to provide an opening, the side margins of the rocker portion being arcuate in plan, the other bearing member provided with flanges adjacent to the arcuate margins, cooperating stud and socket means loosely connecting the bearing members whereby the upper member may rock in a vertical plane and swivel in a horizontal

- plane, and a pin mounted in the flanges and projecting through the opening, the length of said opening being considerably greater than the diameter of the pin to permit of said swiveling.
5. A bearing for a pump operating lever comprising bearing members, the one provided with a semi-cylindrical rocker portion resting on the other, the side margins of the rocker portions being arcuate in plan, the other bearing member provided with flanges adjacent to the arcuate margins, and a swivel joint means loosely articulating said members whereby the upper member may rock in a vertical plane and swivel in a horizontal plane. 85
